Primary Examiner — Vy N Koenig(74) *Attorney, Agent, or Firm* — Cooper & Dunham LLP(57) **CLAIM**

The ornamental design for a step stool, as shown and described.

DESCRIPTION

FIG. 1 is a top perspective view of a step stool in accordance with the present design;

FIG. 2 is a left side view thereof;

FIG. 3 is a right side view thereof;

FIG. 4 is a front view thereof;

FIG. 5 is a back view thereof;

FIG. 6 is a top view thereof; and,

FIG. 7 is a bottom view thereof.

The broken lines depict portions of the step stool that form no part of the claimed design.
